UNITED STATES PATENT OFFICE

NILS D. LEVIN, OF COLUMBUS, OHIO, ASSIGNOR TO THE JEFFREY MANUFACTURING COMPANY, OF COLUMBUS, OHIO, A CORPORATION OF OHIO

APPARATUS FOR LOADING COAL

Application filed September 3, 1924. Serial No. 735,583.

This invention relates to new and useful improvements in apparatus for loading coal. It is designed particularly for use in a chamber of a coal mine to gather coal which has been previously broken down and dislodged along a relatively long face of the vein; convey it to any designated place, and load it, if desired, into suitably placed receptacles for transportation.

10 One object of the invention is to provide conveying mechanism of such construction that it is adapted to extend along a relatively long coal face, and to gather the broken down and dislodged coal from the floor of 15 the mine, when such conveying mechanism is bodily moved laterally and properly positioned with relation to the broken down coal.

A further object is to provide apparatus of the class described which will have lateral 20 flexibility to permit predetermined portions of the gathering mechanism to be independently moved into operative relation to the broken down coal.

A still further object is to provide apparatus 25 of the class described which will have vertical flexibility to permit the gathering mechanism to conform to irregularities of the surface, as, for example, a mine floor, on which it rests.

30 A still further object is to provide a frame construction which reduces the width of the machine to such a degree that roof supporting props may be located outside of the machine, when it is in working position without 35 interfering with its operation, and yet such props will be positioned relatively close to the working face of the vein.

A still further object is to so combine and 40 arrange the parts which make up the apparatus, as to permit convenient disassembling and reassembly of the machine, to facilitate movement of the apparatus from one part of the mine to another.

A still further object is to provide a frame 45 construction which will permit ready adjustment of the effective length of the machine relative to the length of the coal face along which the coal is to be gathered.

In the drawings accompanying the specification 50 which follows, is shown one embodiment

ment of the invention, but it will be understood that the disclosure in the drawings and specification is merely illustrative, and not restrictive of the invention.

In the drawings:—

Fig. 1 is a plan view of the driving, or head, end of my improved coal loading mechanism.

Fig. 2 is a side elevation of the mechanism illustrated in Fig. 1, viewed from the lower side of Fig. 1.

Fig. 3 is a plan view of the foot end of the machine.

Fig. 4 is a side elevation of the devices illustrated in Fig. 3, viewed from the lower side of Fig. 3.

Fig. 5 is a cross sectional view taken along substantially the line V—V of Fig. 1, looking in the direction of the arrows.

Fig. 6 is a cross sectional view taken along substantially the line VI—VI of Fig. 1, looking in the direction of the arrows.

Fig. 7 is a sectional view taken along substantially the line VII—VII of Fig. 6, looking in the direction of the arrows.

Fig. 8 is a plan view, partly in section, showing the articulation of the conveyor frame.

Fig. 9 is a cross sectional view taken along substantially the line IX—IX of Fig. 3, looking in the direction of the arrows.

Fig. 10 is a sectional view taken along substantially the line X—X of Fig. 3, looking in the direction of the arrows.

Figs. 11, 12, and 13 are diagrammatic cross sections of a coal working showing the relation of the apparatus to the coal face and roof supporting props.

Figs. 14 and 15 are diagrammatic illustrations showing two of the many methods of operation of this machine in a coal mine.

Referring to the drawings by numbers, like numbers indicating like parts in the several views, my improved loading apparatus comprises a sectional frame of suitable length adapted to rest upon and slide over the mine floor, and having guideways of proper formation in its lateral edges which receive and in which travels the endless conveyor chain 1, to which are attached the conveyor flights 100

2 by which the coal is gathered and propelled to the point of delivery, as, for example, a suitable receptacle for transportation. The frame above referred to is composed of 5 a plurality of separable sections 3, 4, and 5, which are pivotally connected together in a manner which affords flexibility in both vertical and horizontal planes. The head frame section 3, preferably, and as here 10 shown, supports the power devices by which the conveyor chain 1 is driven, and the foot frame section 5, in this present disclosure, contains the foot wheel around which the chain 1 passes to change its direction of travel. Intermediate these frame sections 3 and 15 5 may be positioned any preferred number of the intermediate frame sections 4 to adjust the overall length of the conveyor to that of the coal face along which the dislodged coal is to be gathered.

This arrangement of frame and conveyor chain, with its attached flights, provides a very flexible arrangement which adapts itself readily in both vertical and horizontal directions to the conditions under which the apparatus is manipulated.

Each of the intermediate frame sections 4 consists of a bottom plate 6 of such construction as to form a suitable support to rest upon 20 and slide over the floor of the mine, or other supporting surface, the forward lateral edge of which plate may be turned downwardly, as shown at 7 in Fig. 6, to insure contact with the mine floor, and eliminate or reduce 25 danger of the plates riding up over loose masses of material. To the plate 6 is secured a pair of angle bars 8 which are joined together at their ends by the hinges 9 and 10, secured, as shown, to the angle bars. The 30 hinge 10 has formed therein a socket 11 adapted to receive the ball 12 of the hinge 9 of the adjacent frame section, and the proportions and assembly of these parts are such that they permit angular movement of 35 adjacent frame sections in both vertical and horizontal directions, and also permit them to be engaged and disengaged by relative vertical movement, as will be clear from Figs. 7 and 8. Mounted on the bars 8, and preferably formed on the hinges 9 and 10, are 40 lugs 13 which project, as here shown, through suitable apertures in the top plates 14, and a key 15, or equivalent device, thrust through an aperture in the lugs 13 locks the top 45 plate 14 against the upper edges of the angle bars 8. The top plate 14 is provided with guide flanges 16 which cooperate with the guide bars 17 secured to the bottom plate 6 to confine the conveyor chain 1 to the guide-way provided by the elements above described, and these guide flanges 16 are preferably and conveniently formed by turning the edges of the plates 14 downwardly.

This construction, which may, of course, 50 be varied with respect to details and mechan-

ical expedients from what is here disclosed, permits the ready taking down or reassembling of the sectional conveyor, so that it may be increased or decreased as to its length at the point of operation, and without the use of special tools or need of skilled mechanics.

The conveyor chain 1 may be of any type suitable to the needs of the work to be done. In the drawings I have shown a chain adapted to flexure in both vertical and horizontal directions, and provided at suitable intervals with coupling links 18 by which said chain may be conveniently uncoupled and reunited to facilitate the addition or subtraction of one or more of the intermediate sections 4, to vary the total length of the conveyor. Such a chain is disclosed in U. S. Patent 1,688,566, issued on October 9, 1928, and need not be further described at this time. When a section of the conveyor is to be inserted in or removed from the conveyor, the top plate 14 may be removed from a conveniently positioned frame section by withdrawing the locking members 15, thereby exposing the conveyor chain 1 to permit of its being uncoupled. After the adjustments are completed and the chain is recoupled, the top plate 14 may be replaced and the chain 1 held in place for service.

Pivottally mounted on the chain 1 for vertical movement, is a series of shovel-like conveyor flights 2 adapted to slide along the upper surface 19 of the bottom plate 6, and beneath the fragments of coal lying thereon, and to carry said coal along said bottom plate. The length of the flights 2 is preferably slightly greater than the width of the surface 19 of the bottom plate to allow the ends of said flights to engage and move the coal upon the mine floor in front of said plate extension, and, furthermore, facilitate bodily lateral movement of the apparatus towards and into the broken coal mass which is to be gathered.

It will be observed that the projecting ends of the flights 2, as here shown, and particularly in Figs. 6, 9 and 10, are beveled downwardly at their ends which project beyond the surface 19 of the bottom plate 6, so that they will slide easily beneath the broken down coal mass, and the downwardly beveled edge 7 of the bottom plate 6 will as readily follow and enter beneath the mass.

To reduce the overall width of the apparatus, and, as a result, decrease the working area necessary for its operation, the bottom plate 6 is cut away or reduced along the outer edge of the guide frame, as shown in Fig. 1, and the conveyor flights 2 are turned upwardly on their pivots, by devices shortly to be described, to a substantially vertical position as they travel along the return side of the conveyor frame. The said flights 2 are maintained in this substantially vertical

position by means of guides 20, here shown as angle strips, which may be suitably supported by supports 21 secured to the top plate 14. These supports 21 also uphold a shield or cover 22, here shown as of inverted 5 V-shape, and which serves to house the upstanding flights and prevent accidental contact with the operator, or other objects external of the apparatus. Lugs 23, (see Figs. 6 and 8) attached at convenient intervals 10 along the rear edge of the bottom plate 6, engage the rear edge of the shield plate 22 to assist in maintaining said plate in operative relation with the returning conveyor flights. 15 The shape and disposition of the shield or cover plate 22 adapts it to act as a side wall for the conveyor trough, the bottom of which is formed by the surface 19 of the bottom plate. It will be seen that this shield or cover plate 22 has two functions. First, it houses 20 the flights 2 as they return in idle position to the foot of the apparatus, and, second, it forms one side of a trough or passageway along and through which the conveyor flights 2, in active working position, move the coal. 25 No side wall is provided or necessary along the opposite side of the conveyor, for the pile of coal upon the mine floor serves to confine the coal upon the bottom plate 19 in the same 30 manner that it would be confined by a side wall, the coal being carried along in the trough formed between the shield 22 and the opposed mass of coal. The lugs 23 may be 35 V-shaped so as to form a convenient means of attachment for moving jacks, hooks, crow-bars, or like devices, utilized to shift and move the apparatus over the mine floor.

The foot section 5 (see Figs. 3, 4, 9 and 10) differs from the intermediate sections 4, 40 in that its bottom plate 24 is expanded laterally at its inner edge to accommodate the foot wheel 25 about which the conveyor chain 1 passes to change its direction of travel. Attached to the bottom plate 24 are chain guideways 26 and 27 substantially similar to those 45 of the intermediate sections. At the inner end of the section 5 which is connected to the adjacent intermediate section, the guideways 26 and 27 are arranged to register with 50 those of the adjacent sections, and these guideways 26 and 27 diverge outwardly, following the widened bottom plate 24 of foot section 5, to guide the chain 1 to and from the foot wheel 25. The hinge member 9 of the 55 section 5 corresponds with those of the other sections of the conveyor. The foot wheel 25 is attached to the lower end of a vertical shaft 28 in a suitable journal bearing 29 formed on a yoke 30, and a thrust collar 31 attached 60 to the upper end of the shaft 28 supports the weight of the wheel and shaft upon the upper end of said journal bearing 29 (see Fig. 10). The thrust collar 31 may be shaped to 65 form an oil receptacle and provide for lubrication of the shaft 28, a convenient lid 32 being provided to close said oil receptacle. The yoke 30 is slidably mounted in guideways formed in the member 33, preferably secured to the bottom plate 24, and an adjusting screw 34 and its cooperating nut 35 afford means 70 for the movement of said yoke and foot wheel relative to the bottom plate 24 to tension the conveyor chain 1 in the manner well understood in the conveyor art.

The guide bar 20, adjacent the foot, is bent 75 outwardly to shift the returning conveyor flights 2 from the positions shown in Figs. 3 and 6, to those shown in Fig. 9, so that they will fall to their horizontal positions. A second guide bar 36, attached to the bottom plate 24, 80 and inclining downwardly to said bottom plate, prevents the flights 2 falling too soon, and eases them down to their final horizontal working position. The second guide bar 36 is so shaped that if the conveyor chain 1 were 85 moved in the reverse direction, the conveyor flights 2 would be turned upwardly to their vertical position to travel along the return strand of the conveyor in the same manner as when traveling in the forward direction. 90 The guide bar 36 may be attached to the bottom plates 24 and to a bracket 37 fastened thereto, by suitable bolts 38 and 39, and a plurality of apertures are provided for the insertion of these bolts to permit the adjustment of said guide bar 36 to correspond with 95 the movement of the foot wheel 25 when adjusting the tension of the chain 1.

The housing 22 is extended over the foot section, being suitably widened, as shown in 100 Fig. 9, and upheld by the supports 21.

With this construction of foot section, it will be seen that it may be readily connected or disconnected with its adjacent intermediate section; that change, adjustment, and 105 tensioning can be readily accomplished, and that the flights, as they pass around the foot wheel, will be straightened, upheld from falling outwardly until they have reached the proper point, and will then be gradually 110 lowered to their horizontal full working position.

The head section 3 of the conveyor is mounted upon a framework having a bottom plate 40 adapted to rest upon and slide in 115 any direction over the mine floor. The edges of the bottom plate 40 are preferably, as shown, upturned, in order that the relatively heavy head section may be readily shifted without danger of the edges of the bottom 120 plate catching upon rough inequalities or projections upon the mine floor, or other supporting surface. Upon this framework is supported the guideways 41 and 42 which are 125 of similar construction to those above described, and a hinge member similar to those described is provided to connect the head section 3 with its adjacent intermediate section. At their inner ends the guideways 41 and 42 130 register with the corresponding guideways

of the adjacent conveyor sections, and they diverge outwardly to guide the conveyor chain 1 to and from the driving sprocket wheel 43. Extending along the forward side of the forward guideway 41 is a conveyor trough having a bottom plate 44 which is adapted to receive the conveyor flights 2, and the moving coal coming from the surface 19 of the adjacent conveyor section, and this plate 44 is bent to form the flaring sidewall 45 of the conveyor trough. The opposite wall of the trough is formed by the vertical plate 46 which is also a part of the shield structure 47.

The guideways 41 and 42 and the trough 44 are curved upwardly and then outwardly, in order that they may project when the material is to be delivered to a receptacle, above the point of deposit on the receptacle to which the dislodged coal is to be delivered. A semi-circular extension 48 of the bottom plate 44 projects beyond the periphery of the sprocket wheel 43 to prevent the conveyor flights falling, and maintain them in substantially horizontal position as they pass around the sprocket wheel. As the flights 2 leave the sprocket wheel 43 for the return movement, they are engaged by a guide bar 49, so positioned that they are turned upwardly into their substantially vertical idle position, and pass to the guide bar 20 of the return run of the conveyor.

The head sprocket wheel 43 is mounted for free rotation about a stationary vertical shaft 50 fixed to the frame, and to its extended hub 51 is secured a bevel gear 52. The bevel gear 52 is engaged by a bevel pinion 53 fixed to the horizontal driving shaft 54, which is supported in suitable bearings 55 on the frame. To the driving shaft 54 is fixed a hub 56 having a radially extending flange 57, and a sprocket wheel 58 is freely mounted upon the shaft 54 adjacent the flange 57. The sprocket wheel 58 is connected with the shaft 54 by a shear pin 59 which projects through registering apertures of the sprocket wheel 58 and flange 57, this shear pin constituting a safety coupling device by which the power which may be transmitted to the head shaft of the conveyor is limited, so that breakage or derangement of the driven parts under overload is effectively guarded against. An endless chain 60 connects the sprocket wheel 58 with a sprocket wheel 61, which is directly attached to a spur gear 62. The spur gear 62 engages the armature pinion 63 of the motor 64 to drive the conveyor.

The motor 64 may be of any preferred type suitable to the conditions under which the machine operates. For purposes of illustration I have shown an electric motor adapted to receive its actuating current from any convenient source of electric supply through a suitable conductor, not shown in the drawings, and to be controlled by a suitable con-

trolling mechanism 65 which is preferably mounted upon the side of the motor frame. As these devices are well understood in the art, and as they form no part of the present invention, further description is thought to be unnecessary.

In Fig. 14 I have illustrated a mining operation involving the use of my improved coal handling machine, this operation showing the loading of coal into cars. As a preliminary development operation a pair of spaced apart parallel entries 66 are driven across the territory to be mined, and in these entries are laid the tracks 67 over which travel the cars 68 by which coal is transported from the mine. Room entries 69, extending parallel with and adjacent the haulage entries 66 are driven, and suitable breakthroughs 70 are provided to afford the ventilation which is required. The room entries 69 are so spaced from the haulage entries 66 that the intervening pillar of coal will be of sufficient thickness to afford safe support for the roof of the haulage entries during all stages of operation. Preparatory to the installation of my improved loading machine, relatively narrow rooms 71, 72, 73, 74, etc., are driven between the entries 69, preferably in alignment with the breakthroughs, and these rooms provide the relatively long working faces required for the economical operation of my machine. The entries, rooms, and breakthroughs, above described, may be driven in any preferred manner suitable to the existing conditions. Use is here contemplated of entry driving machines such as are disclosed in my copending application, Serial No. 697,790, filed March 8, 1924, and such machines are indicated at 75 in Fig. 14, working towards each other to form the room 74.

In each of the rooms 72 and 73 are installed two loading machines 76, the length of which have been so adjusted that their foot sections 5 may lie in close proximity to each other midway the length of the room, while their head sections 3 are in the entries 69.

As a means for collecting the coal from the several machines involved in this operation, I have provided elongated, continuously moving conveyors 77, which may be of any preferred type, such as belt conveyors, scraper conveyors, or the like, and these conveyors extend along the entries 69 and discharge into a similar cross conveyor 78. Branch conveyors 79 of the same general type, are also placed in the rooms 74 to receive the coal from the entry driving machines 75 and transfer it to the main entry conveyors 77. The cross conveyors 78 are positioned in convenient breakthroughs, and are adapted to deliver a continuous flow of coal to the cars 68 of a moving train as they pass along the haulage track 67 beneath the end of the cross conveyor 78. By this means interruption of the operation of the several

mining machines to permit the movement of cars is avoided for long periods of time, and if proper attention is paid to the manipulation of the trains of cars upon the mine tracks, such interruption need never occur.

5 The principal mining operation which is conducted along the rib face of each room is as follows: The coal is first undercut, preferably by a machine 80 of the well known longwall type having a frame adapted to slide along the mine floor between the loading machine and the coal face, and having a cutter arm adapted to extend perpendicularly to the coal face and to cut a kerf therein as the machine moves. After being undercut, the coal is dislodged in any suitable manner, such as by blasting, and the shattered and loosened coal falls downwardly and outwardly in a pile extending along the entire 10 face of the room. The foot section 5 of the loading machine may then be moved forwardly to cause the flights 2 to engage the broken coal upon the mine floor and move it longitudinally of the machine towards the 15 entry 69 where it is discharged into the entry conveyor 77. As the work progresses each successive section of the loading machine is moved towards the dislodged coal until all of 20 said coal has been loaded.

25 If the vein be of sufficient thickness, the coal dislodged from the upper part of the vein may be thrown outwardly a sufficient distance to fall upon the bottom plate 19 and the conveyor flights 2, and this coal may be 30 of sufficient bulk to overload the driving mechanism and stall the conveyor. To guard against such a contingency, I provide a plurality of short boards 81 (see Figs. 26 and 13) which I place above the conveyor trough, 35 one end resting upon the ground adjacent the coal face, and the other end resting upon the V-shaped shield or cover 22 of the loading machine. These boards support the dislodged coal above the conveyor, and may be 40 progressively removed to allow the dislodged coal to fall upon the conveyor to be transported thereby. When such boards 81 are 45 used, I preferably move the loading machine close to the coal face, as illustrated in Fig. 13, 50 and place the boards in position before shooting. The greater part of the dislodged coal 55 will then rest upon the boards 81, and can be fed to the conveyor by their progressive removal, greatly facilitating the loading operation.

Roof supporting props 82 are commonly placed immediately behind the loading machine, as shown in Figs. 11, 12 and 13, and these props extend in a row substantially 60 parallel to the coal face. Frequently roof conditions are such that the props 82 must be placed so close to the coal face as to leave barely sufficient room for the loading machines, no space being available for the passage 65 of the undercutting machine 80. In

such cases the flexibility of the loading machine frame (see Fig. 15) permits a single section to be moved back from the coal face, the roof props adjacent that section being temporarily removed. As the cutting progresses each successive section of the loading machine is moved back from the wall, and those in the rear of the cutting machine, and the accompanying roof props, are immediately restored to their initial position. Such an operation is shown at 83 in Fig. 15. Under some circumstances the cutting machines may slide over the trough plate 19 of the loading machine as shown in Fig. 12, the successive conveyor flights 2 being turned to a vertical position as the cutting progresses.

70 Where roof conditions will permit, a better recovery may sometimes be attained by a short panel system such as is illustrated in Fig. 15. In the development of such a system, pairs of entries 84 are driven across the territory to be mined, and these are connected by cross passages 85 dividing the coal body into rectangular panels. The principal mining operations are conducted along the ribs 75 of the entries 84 extending from one cross passage 85 to the next, and these cross passages are spaced a sufficient distance apart to permit the economical operations of my improved loading machine 86, one of which is 80 installed upon each of these working faces. Loading conveyors 87 and 88 receive the coal discharged by these loading machines and deliver it to the cars 89 of a train upon the mine track 90. The mining operation upon each 85 working face is substantially like that described in the room and pillar system, the coal being undercut, broken down, and gathered in the same manner. In order to afford the greatest possible protection to the loading machines 86 and to the conveyors 87, the successive faces 91, 92, and 93 are progressively offset as shown, all of the apparatus 90 being gradually withdrawn towards the mouth of the mine.

95 It is to be understood that the methods of operation above described are but illustrative of some of the uses of my improved apparatus for loading coal; that these methods may be subject to wide variation, and that many other uses will suggest themselves to persons skilled in the art without departure from the spirit of my invention. Furthermore, such changes in construction and the adoption 100 of expedients other than and equivalent to those herein disclosed as are within the range of mechanical skill, may be made, and still be within the purview of my invention.

105 While the apparatus is here shown for gathering, and for loading, material, it will be obvious that it might be used for operations other than the specific uses herein described.

I claim:

110 1. In a conveyor, an endless conveyor

- chain, flights pivoted thereto, means for swinging the flights during their travel in planes transverse to the line of the chain for rendering them inoperative, and means for positively moving them toward normal operative position.
2. In a conveyor, an endless conveyor chain, flights pivoted thereto, means for swinging the flights during their travel in planes transverse to the line of the chain for rendering them inoperative, and a cam surface adapted to be engaged by the flights for positively moving them toward operative position.
3. In a conveyor, an articulated support, an endless conveyor chain traveling thereon, flights pivoted to said chain, means for swinging the flights during their travel in planes transverse to the line of the chain for rendering them inoperative, and aligned guide rail sections on said support for guiding said inoperative flights, said flights having cam surfaces for contact with said sections.
4. In a conveyor, an articulated support, an endless conveyor chain traveling thereon, flights pivoted to said chain, means for swinging the flights during their travel in planes transverse to the line of the chain for rendering them inoperative, and shield sections on said support for the inoperative flights.
5. In a conveyor, an articulated support, an endless conveyor chain traveling thereon, flights pivoted to said chain, means for swinging the flights during their travel in planes transverse to the line of the chain for rendering them inoperative, shield sections on said support for the inoperative flights, and guide rail sections for the inoperative flights fixed to said shield sections.
6. In a machine of the class described, the combination of a frame, an endless chain mounted thereon, means for driving said chain, gathering elements movably mounted on said chain and adapted to lie in a substantially horizontal active position, and means for moving said gathering elements to a substantially vertical inactive position during a predetermined portion of their travel.
7. In a machine of the class described, the combination of a frame, an endless chain mounted thereon, driving means therefor, gathering elements pivotally mounted on said chain adapted to lie in a substantially horizontal active position, means automatically to move said gathering elements to a substantially vertical inactive position during a predetermined portion of their travel, and means automatically to move them toward their active position.
8. In a machine of the class described, the combination of a frame, an endless chain mounted thereon, driving means therefor, gathering elements pivotally mounted on said chain adapted to lie in a substantially horizontal active position, means automatically to move said gathering elements to a substantially vertical inactive position during a predetermined portion of their travel, means automatically to move them toward their active position, and means for housing said elements when in inactive position.
9. In a machine of the class described, the combination of a relatively narrow frame having a widened head section, a power unit on said head section; an endless chain driven from said power unit, gathering flights on said chain adapted to lie in a substantially horizontal active position on one side of said frame, and means at the head end of said frame to move said gathering flights to a substantially vertical inactive position on the other side of said frame.
10. In a machine of the class described, the combination of a relatively narrow frame having a widened head section, a power unit on said head section; an endless chain driven from said power unit, gathering flights on said chain adapted to lie in a substantially horizontal active position on one side of said frame, means at the head end of said frame to move said gathering flights to a substantially vertical inactive position on the other side of said frame, and means at the other end of said frame to move said gathering flights toward their active position.
11. In a machine of the class described, the combination of a relatively narrow frame having a widened head section, a power unit on said head section, an endless chain driven from said power unit, gathering flights pivotally mounted on said chain adapted to lie in a substantially horizontal active position on one side of said frame, guide members at the head end of said frame automatically to move said flights to a substantially vertical inactive position on the other side of said frame, and guide members at the foot end of said frame automatically to guide said flights to their active position.
12. In a machine of the class described, the combination of a relatively narrow frame having a widened head section, a power unit on said head section; an endless chain driven from said power unit, gathering flights pivotally mounted on said chain adapted to lie in a substantially horizontal active position on one side of said frame, guide members at the head end of said frame automatically to move said flights to a substantially vertical inactive position on the other side of said frame, guide members at the foot end of said frame automatically to guide said flights to their active position, and means for housing said flights in their inactive position.
13. In a machine of the class described, the combination of a relatively narrow frame having a widened head section, a power unit on said head section, a material receiving

trough on one side of said head section, an endless chain driven from said power unit, gathering flights pivotally mounted on said chain adapted to lie in a substantially horizontal active position on one side of said frame, guide members at the head end of said frame automatically to move said flights to a substantially vertical inactive position on the other side of said frame, guide members at the foot end of said frame automatically to guide said flights to their active position, and means for housing said flights in their inactive position.

14. In a machine of the class described, the combination of a relatively narrow frame having a widened head section, a power unit on said head section, a material receiving and elevating trough on one side of said head section, an endless chain driven from said power unit, gathering flights pivotally mounted on said chain adapted to lie in a substantially horizontal active position on one side of said frame, guide members at the head end of said frame automatically to move said flights to a substantially vertical inactive position on the other side of said frame, guide members at the foot end of said frame automatically to guide said flights to their active position, and means for housing said flights in their inactive position.

15. In a machine of the class described, a horizontally flexible frame having a head section and a foot section, a power unit mounted on one of said sections, an endless chain on said frame driven from said power unit, gathering flights pivotally connected with said chain adapted to lie in a substantially horizontal active position on one side of said frame, and means at one end of said frame automatically to move said gathering elements to a substantially vertical inactive position on the other side of said frame.

16. In a machine of the class described, a horizontally flexible frame having a head section, a foot section, and a plurality of interconnected intermediate sections, a power unit mounted on one of said sections, an endless chain on said frame driven from said power unit, gathering flights pivotally connected with said chain adapted to lie in a substantially horizontal active position on one side of said frame, and means at one end of said frame automatically to move said gathering elements to a substantially vertical inactive position on the other side of said frame.

17. In a machine of the class described, the combination with an elongated frame adapted to rest upon and slide over the floor of the mine, said frame comprising a plurality of longitudinally disposed sections pivotally connected together for relative angular movement in horizontal planes, an endless flexible draft device adapted to travel in guideways extending longitudinally of

said frame, a laterally projecting plate extending along each section of said frame adapted to contact with the mine floor, and laterally projecting conveyor elements carried by said draft device and adapted to propel loose material along said plates as and for the purpose set forth. 70

18. In a machine of the class described, the combination with an elongated frame adapted to rest upon and slide over the floor of the mine, said frame comprising a plurality of longitudinally disposed sections pivotally connected together for relative angular movement in both vertical and horizontal planes, an endless flexible draft device adapted to travel in guideways extending longitudinally of said frame, a laterally projecting plate extending along each section of said frame and adapted to contact with the mine floor, and laterally projecting conveyor elements carried by said draft device and adapted to propel loose material along said plates as and for the purpose set forth. 75 80

19. In an apparatus of the class described, the combination with an elongated frame comprising a plurality of longitudinally disposed frame sections, conveying mechanism mounted upon said sections and adapted to convey material longitudinally of said frame, and means connecting said sections for permitting angular operating relations thereof and adapted to be engaged or disengaged by relative vertical movement of said frame sections. 90 95

20. In an apparatus of the class described, the combination with an elongated frame comprising a plurality of longitudinally disposed frame sections, of conveying mechanism mounted upon said sections and adapted to convey material longitudinally of said frame, and means adapted to be engaged or disengaged by relative vertical movement of said frame sections to connect their adjacent ends for relative angular movement in horizontal planes as and for the purpose set forth. 100 105

21. In an apparatus of the class described, the combination with an elongated frame comprising a plurality of longitudinally disposed frame sections, conveying mechanism mounted upon said sections and adapted to convey material longitudinally of said frame, and means adapted to be engaged or disengaged by relative vertical movement of said frame sections to connect their adjacent ends for relative angular movement in vertical planes as and for the purpose set forth. 110 115

22. In an apparatus of the class described, the combination with an elongated frame comprising a plurality of longitudinally disposed frame sections, conveying mechanism mounted upon said sections and adapted to convey material longitudinally of said frame, and means adapted to be engaged or 120 123 130

disengaged by relative vertical movement of said frame sections to connect their adjacent ends for relative angular movement in both vertical and horizontal planes.

23. In a machine of the class described, the combination with an elongated frame having longitudinally extending guideways formed in its lateral edges, of an endless flexible draft device adapted to travel in said guideways, conveyor flights hinged to said draft device for pivotal movement in planes extending transversely of said draft device, guiding means extending along the forward side of said frame adapted to support said conveyor flights in horizontal extension, and guiding means extending along the rearward side of said frame adapted to hold said conveyor flights in vertical extension as and for the purpose set forth.

24. In a machine of the class described, the combination with an elongated frame having longitudinally extending guideways formed in its lateral edges, of an endless flexible draft device adapted to travel in said guideways, conveyor flights hinged to said draft device for pivotal movement in planes extending transversely of said draft device, guiding means extending along the forward side of said frame adapted to support said conveyor flights in horizontal extension, guiding means extending along the rearward side of said frame adapted to hold said flights in vertical extension, and means at the ends of said frame to turn said flights to or from vertical extension as and for the purpose set forth.

25. In a machine of the class described, the combination with an elongated frame having longitudinally extending guideways formed in its lateral edges, of an endless flexible draft device adapted to travel in said guideways, conveyor flights hinged to said draft device for pivotal movement in planes extending transversely of said draft device, guiding means extending along the forward side of said frame adapted to support said conveyor flights in horizontal extension, guiding means extending along the rearward side of said frame adapted to hold said conveyor flights in vertical extension, and a shield to protect said vertical flights from accidental contact with objects external of the machine.

26. In a machine of the class described, the combination with an elongated frame having longitudinally extending guideways formed in its lateral edges, of an endless flexible draft device adapted to travel in said guideways, conveyor flights hinged to said draft device for pivotal movement in planes extending transversely of said draft device, guiding means extending along the forward side of said frame adapted to support said conveyor flights in horizontal extension, guiding means extending along the rearward side of said frame adapted to hold said flights in vertical extension, and a shield adapted to protect

said vertical flights from accidental contact with objects external of the machine and to confine loose material to the forward side of said frame as and for the purpose set forth.

27. In a machine of the class described, the combination with a conveyor frame, of an endless flexible draft device carried thereby, a guideway in said frame along which said draft device is adapted to travel, a side of said guideway being readily removable to afford access to said draft device as and for the purpose set forth.

28. In a machine of the class described, the combination with a conveyor frame, of an endless draft device carried thereby, a guideway in said frame along which said draft device is adapted to travel, a side of said guideway being readily removable to afford access to said draft device, and readily disengageable devices adapted to lock the removable side of said guideway in operative position as and for the purpose set forth.

29. In a conveyor frame, the combination with a bottom plate, of upwardly projecting flanges secured to said plate, a top plate engaging the upper edges of said flanges and cooperating with said bottom plate and said flanges to form guideways along which the conveyor chain is adapted to travel, and readily detachable means to lock said top plate in operative position relative to said flanges as and for the purpose set forth.

30. In a conveyor frame, the combination with a bottom plate, spaced apart upwardly projecting flanges secured to said plate, a top plate engaging the upper edges of said flanges and cooperating with said bottom plate and said flanges to form guideways along which the conveyor chain is adapted to travel, lugs attached to said flanges and projecting upwardly through apertures of said top plate, and keys engaging said lugs to lock said top plate in operative relation with said flanges as and for the purpose set forth.

31. In a machine of the class described, a vertically flexible frame having a head section, a foot section, and a plurality of interconnected intermediate sections, a power unit mounted on one of said sections, an endless chain on said frame driven from said power unit, gathering flights pivotally connected with said chain adapted to lie in a substantially horizontal active position on one side of said frame, and means at one end of said frame automatically to move said gathering elements to a substantially vertical inactive position on the other side of said frame.

32. In a machine of the class described, a vertically and horizontally flexible frame having a head section and a foot section, a power unit mounted on one of said sections, an endless chain on said frame driven from said power unit, gathering flights pivotally connected with said chain adapted to lie in a substantially horizontal active position on

one side of said frame, means at one end of said frame automatically to move said gathering element to a substantially vertical inactive position on the other side of said frame.

33. In a conveyor, an elongated base plate composed of articulated sections, an endless chain traveling from end to end of said plate, the advancing and returning sections of said 10 chain being disposed in substantially the same horizontal plane, horizontally extending material engaging elements secured at one end to said chain and traveling over said plate, the free ends of said material engaging 15 elements on the advancing section of the chain projecting slightly beyond the adjacent lateral edge of the base plate, said sections being relatively angularly movable in the normal horizontal planes of flexure of the 20 chain to conform substantially to the irregular outlines of a pile of material to engage the material engaging elements therewith.

34. In a conveyor, an elongated base plate composed of articulated sections, an endless 25 chain travelling from end to end of said plate with a working section disposed for normal flexure in horizontal planes, and horizontally extending material engaging elements secured at one end to said chain and extending 30 transversely of said plate with the other end adjacent an unobstructed lateral edge of the plate, said sections being relatively angularly movable in the horizontal planes of flexure of the chain to conform substantially 35 to the irregular outlines of a pile of material to engage the material engaging elements therewith.

35. In a conveyor, an elongated base plate composed of articulated sections, an endless 40 chain travelling from end to end of said plate with a working section disposed for normal flexure in horizontal planes, and horizontally extending material engaging elements secured at one end to said chain and extending 45 transversely of said plate with the other end adjacent an unobstructed lateral edge of the plate, an upwardly extending wall on said plate to the side of said working section opposite from the material engaging elements, 50 said sections being relatively angularly movable in the horizontal planes of flexure of the chain to conform substantially to the irregular outlines of a pile of material to engage the material engaging elements therewith.

36. In a conveyor, an elongated base plate, composed of articulated sections, an endless chain travelling from end to end of said plate, and comprising a working and an 55 idling section, said working section being adapted for normal flexure in horizontal planes, flights secured at one end to said chain, the flights on the working section extending horizontally and transversely over the plate 60 toward an unobstructed edge of the latter,

means for swinging the flights on the idling section into substantially vertical position, and a housing for such vertically positioned flights, said sections being relatively angularly movable in the horizontal planes of 70 flexure of the chain to conform substantially to the irregular outlines of a pile of material to engage the flights therewith.

37. In a longwall mining conveyor and loader the combination of a plurality of pivotally connected ground supported plate sections, an endless member movably connected with said plates and operable thereover, each of said plates at a longitudinal side thereof being unobstructed, tines pivotally connected 75 with said endless member for pivotal movement in substantially a vertical plane, said tines at the unobstructed sides of said plates being adapted for horizontal resting on said plates for coal conveying purposes, and 80 means along the opposite sides of said plates for moving and supporting the tines in upright position.

38. As an article of manufacture a conveyor for mining operation comprising a 85 flat shallow plate constructed to be substantially horizontally positioned in ground engagement adjacent the base of a seam, and having a longitudinal edge thereof unobstructed, and an endless conveyor operating upon said plate including laterally extending coal conveying tines horizontally operating over the plate adjacent said unobstructed edge.

39. In a longwall mining conveyor comprising a plurality of flat, shallow and elongated plates each having the same side thereof unobstructed to permit said plates to be laterally moved toward a face of a coal seam to permit the plates to conform to irregularities in the face of the seam, and an endless chain operably connected over said plates including laterally extending tines operating horizontally over said plates along the unobstructed edges thereof for 100 conveying coal which falls upon said plates, all of said plates being connected in substantially the same plane.

40. In a conveyor and loading machine for mining a horizontally disposed ground engaging plate, an endless belt operable over said plate including laterally extending tines, said plate at one side of the endless conveyor being adapted to horizontally receive the tines thereover in unobstructed relation, said plate at said side of the conveyor being laterally unobstructed so that it may be moved into a body of coal to permit the coal to move laterally over the plate and to be conveyed therealong by said tines which are horizontally positioned at said side of the conveyor, means at the opposite sides of the conveyor to collapse the tines, and a guard for disposition over said collapsed 115 120 125 130

tines at said opposite side of the conveyor from the loading side.

41. In a conveyor and loader for mining the combination of a shallow base plate, 5 an elongated endless chain operable over the plate including laterally extending tines, said plate at one longitudinal side being laterally unobstructed and at the opposite side having a stationary rest extension upwardly therefrom upon which workmen may 10 kneel to lean over and operate at the loading side of the conveyor.

42. In a loading conveyor the combination of a plurality of sections including supporting plates, an endless chain, means on said sections movably connecting the endless chain thereon in a guided relation thereover for pivoted connection of said sections, and flights for the endless chain operable over 20 the plates of said sections for coal conveying purposes.

43. In a loading conveyor the combination of a plurality of sections including supporting plates, an endless chain, means on said sections movably connecting the endless chain thereon in a guided relation thereover for pivoted connection of said sections, and flights pivotally connected to said endless chain for movement with respect thereto in 25 a vertical plane, said flights being adapted for cooperation over the plates of said sections for coal conveying purposes at one side of each of said sections, and means at the other side of each of said sections for 30 collapsibly supporting said flights in an upright relation during movement of the chain and flights therewith.

44. In a loader conveyor the combination of a loader head, a tail section, intermediate 40 sections, each of said sections including a ground supporting plate adapted to rest directly on a ground surface, an endless chain, means on said loader head, and tail and intermediate sections forming a continuous groove 45 for receiving said endless chain therein in a movable connected relation upon said sections whereby to pivotally connect said sections with the plates thereof disposed in a horizontal plane for relative movement, and collapsible flights supported upon said plates of the sections in a pivoted connected relation 50 with said endless chain.

45. In a loading conveyor of the class described a plurality of sections including 55 ground supporting platforms for direct support upon the ground, an endless chain, means on said platforms of said sections for receiving the endless chain, pivoted flights 60 upon said chain for extension at one side of each of said sections horizontally over the platforms of the sections for coal conveying purposes, a guide rail carried by each of said sections at the opposite side, said guide 65 rails of the various sections being in substantial

alignment, and means upon an end section of the conveyor for collapsing said flights upon said rails as the flights move about said end section.

46. In a loading conveyor of the class described a plurality of sections including 70 ground supporting platforms for direct support upon the ground, an endless chain, means on said platforms of said sections for receiving the endless chain, pivoted flights upon 75 said endless chain for extension at one side of each of said sections horizontally over the platforms of the sections for coal conveying purposes, and a guide rail carried by each of said sections at the opposite side, said guide 80 rails of the various sections being in substantial alignment, means upon an end section of the conveyor for collapsing said flights, and means at the other end section of said conveyor for extending said flights from a collapsed relation to a coal conveying position 85 over the platform of said sections.

47. In a loading conveyor the combination of a plurality of sections, each of said sections including a shallow ground supporting 90 platform, an endless chain operably connected upon said platforms for pivotally connecting said platforms, said chain being disposed upon said platforms more to one side than the other to provide a loading extension of 95 the platform for each section, tines pivotally connected with said endless chain adapted for horizontal positioning over the loading extensions of said platforms, means at the opposite sides of said platforms from the loading extensions for upwardly collapsing the tines over said platforms, and elongated 100 guard housings individually provided for each section for receiving the collapsed tines therein.

48. In a loading conveyor of the class described the combination of a plurality of pivotally connected sections including platforms, an endless chain mounted on the platforms to provide loader extensions of said platforms to one side of the chain for each section, collapsible tines pivoted on the endless chain operable over the loader extensions of said plates, means to collapse the flights at one end of the conveyor, means to extend the flights at the opposite end of the conveyor, and guard means along said sections for housing the collapsed flights.

49. In a loader conveyor the combination of a plurality of horizontally movable vertically pivoted sections, each of said sections including a platform, an endless chain, means mounting the endless chain for horizontal operation over all of said platforms of the sections, and flights carried by the chain operable over the platforms of said sections.

50. In a loader conveyor the combination of a plurality of elongated plates, and an endless flight carrying conveyor chain connected upon said plates for movement in a 130

defined path and including universally pivoted links to permit vertical and horizontal pivoted movement of the plates with respect to each other.

5 51. In a portable conveyor a horizontally extending elongated plate, an endless draft element comprising horizontally spaced advancing and returning sections traveling along said plate, horizontally extending pivotally mounted material engaging devices on the advancing section of said draft element, means to swing said material engaging devices upwardly on the returning section of said draft element, a vertically extending 10 housing for the material engaging devices on said returning section, said housing being mounted on said plate, and cover means removably supportable at one end by said housing in inclined position above and free 15 of said horizontally extending material engaging devices.

52. In a system for removing coal from a mine working, an elongated conveyor comprising a horizontal plate having an unobstructed edge and an upwardly extending housing portion spaced from said edge, an endless draft element having advancing and returning sections traveling over said plate in a substantially horizontal orbit, material 20 engaging flights pivoted to said draft element on axes parallel to the longitudinal lines of the draft element, the flights on the advancing section extending substantially horizontally over said plate intermediate 25 said unobstructed edge and said housing portion, means for swinging the flights on the returning section upwardly for shielded travel within said housing portion, said conveyor being adapted to be disposed in spaced 30 relation to and along a mine wall with its exposed edge faced toward said wall, a series of strips inclined upwardly transversely of said plate over and free of said horizontally extending flights and supported at their upper 35 ends by said housing portion when the conveyor is disposed along the mine wall, said strips forming a lateral confining wall for the disrupted coal upon the breaking down of an increment from the mine wall and serving to shield said horizontally extending flights from such disrupted material, said strips being removable to release the disrupted material gradually to the conveyor 40 for removal thereby.

55 In testimony whereof I have hereunto set my hand.

NILS D. LEVIN.
